DETACHABLE HEEL

George H. Gillis, Fitchburg, Mass., assignor to
Gilcord Shoe Company, Fitchburg, Mass.

Application May 25, 1938, Serial No. 209,867

10 Claims. (Cl. 36—36)

This invention relates to detachable heels for boots and shoes and has for an object to provide an individual heel and heel base provided with cooperating parts for securely but detachably fixing the heel to the base.

5 A further object is to provide means for preventing the entry of water past the heel base to the shoe sole.

Further objects and advantages will appear from a more complete description of certain 10 embodiments of the invention disclosed in the accompanying drawing in which—

Figure 1 is a perspective view of a rubber heel base and heel secured together.

15 Figures 2 and 3 are perspective views of the heel base and the heel, respectively.

Figures 4 and 5 are sectional views on lines 4—4 and 5—5, respectively, of Figure 1.

20 Figure 6 is a fragmentary view partly in section and partly in elevation of the heel end of a shoe showing the manner in which the heel is attached to and detached from the heel base.

Figure 7 is a fragmentary rear perspective view showing means for preventing the entry of 25 water to the sole member.

Figure 8 is a detail section on line 8—8 of Figure 7.

Figures 9 and 10 are detail perspective views showing other elements for the same purpose.

30 Figure 11 is a view similar to Figure 8, but showing the element of Figures 9 and 10 in position.

Figure 12 is a view similar to a portion of Figure 11, but showing a further modification.

35 Referring to the drawing, at 1 is indicated a heel base adapted to be secured to the heel portion of a shoe by any suitable means such as nails, cement, or both. Extending backwardly from the breast face 2 of this heel base is a dovetail opening 3 having sides 4 with their top and bottom edges, respectively, parallel, but their bottom edges being closer than their upper edges. The rear face 5 of this opening is also cut upwardly and backwardly on a bevel as shown best in Figure 6. At the heel end the heel base is provided with a heightwise notch 7, and preferably the forward wall of this notch is formed upwardly and forwardly beveled as at 8. The heel 40

10 is provided with a dovetail projection or extension 11 on its upper face and extending rearwardly from the breast 12, this extension being dovetailed, having the inclined side faces 13 arranged to mate with the faces 4 of the heel base, and a rear inclined face 14 arranged to mate the face 5 of the heel base when the heel is assem-

bled on the base. At its rear end the heel has an upwardly extending portion 15 shaped generally complementary to the notch 7 of the heel base.

The heel is assembled on the base by inserting 5 the extension 11 into the forward open end of the opening 3 of the heel base and then the heel is pushed rearwardly so as to cause the extension 11 to pass into and fill the opening 3, and when its rear face 14 engages the face 5 of the 10 heel base, the rear end of the heel may then be pushed upwardly, bringing the projection 15 into the notch 7. The inclined face 8 of the notch 7 and the matingly inclined face 16 of the extension 15 then tend to hold the extension 15 in 15 position. It has been found in practice that where a heel is secured to the base at its forward end, the rear end of the heel must be left free for a certain amount of play in order that the heel may remain secured in flat condition to the heel base. For this reason the rear end of the heel is allowed some freedom of motion relative 20 to the heel base and to the shoe.

With the construction heretofore described, 25 difficulty may be experienced in service, if this is not provided for, by reason of the tendency for the notch 7 to open up or spread, permitting the entry of water around the extension 15 and past the heel base to the sole member of the shoe to which the base is secured and eventually this 30 water might work in through or past the sole member to the interior of the shoe. Means are therefore provided for holding these side portions against such spreading action. One means for doing this is illustrated in Figures 7 and 8 wherein a rubber strip 20 secured to the rear face of the heel base at one side of the notch 7 is brought around back of the extension 15 and secured by any suitable means to the heel base at the other side of the notch 7, and preferably 35 in order to effect a certain amount of sealing between the heel base and the heel, this strip is of sufficient width to bridge down over the joint between the heel and heel base, as shown best in Figure 7.

40 In place of an elastic tie to prevent the spreading of the rear end of the notch 7, a more rigid tie may be employed such as that shown in Figure 9, wherein a plate of any suitable material such as metal, Bakelite or other relatively non-expansive material bridges across the notch 7 of the heel base. This plate 25 may be secured by any suitable means such as tacks or the like which may be passed through holes 26 in the plate and driven or otherwise secured in the heel. 45 50 55

base at opposite sides of the notch. The lower corners of this plate are shown as rounded off and the plate is shown of a width greater than that of the heel base so as to extend down over 5 the back of the heel and tend to close the junction between the heel and the heel base.

In order that the plate may be more readily detachable when this is desired, such a plate 25a, as shown in Figure 10, may be provided at one 10 end with a fastener-receiving perforation 26 and at the other with a latching notch 27, which may be swung up into contact with a latching pin or nail. Due to the fact that the base and heel are 15 preferably formed of rubber or similar somewhat yielding material, the notched end of the plate 25a may be readily snapped into latching contact with its mating pin projecting from the heel base.

Figure 12 shows a further modification in which 20 the spreading of the rear end of the notch 7 and sealing protection between the heel base and the heel is accomplished by the provision of an endless band or loop 30, preferably stretchable, such as a rubber band, which surrounds the heel and base and bridges their outer edge faces. This 25 band or loop may, if desired, be cemented or otherwise secured to one of the parts bridged. For example, it may be secured to the base on opposite sides of the notch 7 similarly to the 30 rubber strip 20 of Figure 7. Particularly where the heel breast face is concaved laterally, it may be secured to this face also, either temporarily or in such a manner that it may be loosened or 35 distorted to permit the detachment and replacement of the heel.

From the foregoing description of certain embodiments of this invention, it should be evident to those skilled in the art that various changes and modifications might be made without departing 40 from the spirit or scope of this invention as defined by the appended claims.

I claim:

1. In combination, a heel base having a dovetail opening extending back from its breast face 45 and a heightwise notch extending inwardly from its rear face, and a heel having a dovetail projection on its top face formed to enter said opening at its forward end and to be moved rearwardly into full engagement with the walls thereof and a 50 projection at its rear end formed to engage in said notch when said heel has been moved rearwardly to its limit of motion.

2. In combination, a heel base having a dovetail opening extending back from its breast face 55 and a heightwise notch extending inwardly from its rear face, and a heel having a dovetail projection on its top face formed to enter said opening at its forward end and to be moved rearwardly into full engagement with the walls thereof and a 60 projection at its rear end formed to engage in said notch when said heel has been moved rearwardly to its limit of motion, said projection having an undercut beveled forward edge, the forward edge of said notch being complementally beveled.

3. In combination, a heel base having a dovetail opening extending back from its breast face and a notch extending inwardly from its rear face, a heel having a dovetail projection on its top face 70 formed to enter said opening at its forward end and to be moved rearwardly into full engagement with the walls thereof and a projection at its rear end formed to engage in said notch when said heel has been moved rearwardly to its limit of motion, and tie means engaging said heel base 75

on opposite sides of said notch for preventing the spreading of the sides of said notch which would permit the entry of water during service.

4. In combination, a heel base having a dovetail opening extending back from its breast face and a notch extending inwardly from its rear face, a heel having a dovetail projection on its top face 10 formed to enter said opening at its forward end and to be moved rearwardly into full engagement with the walls thereof and a projection at its rear end formed to engage in said notch when said heel has been moved rearwardly to its limit of motion, and tie means engaging said heel base on opposite sides of said notch and overlapping said heel for preventing the spreading of the 15 sides of said notch.

5. In combination, a heel base having a dovetail opening extending back from its breast face and a notch extending inwardly from its rear face, a heel having a dovetail projection on its 20 top face formed to enter said opening at its forward end and to be moved rearwardly into full engagement with the walls thereof and a projection at its rear end formed to engage in said notch when said heel has been moved rearwardly to its 25 limit of motion, and an elastic strip secured to said heel base on opposite sides of said notch for at least the full width thereof.

6. In combination, a heel base having a dovetail opening extending back from its breast face 30 and a notch extending inwardly from its rear face, a heel having a dovetail projection on its top face formed to enter said opening at its forward end and to be moved rearwardly into full engagement with the walls thereof and a projection 35 at its rear end formed to engage in said notch when said heel has been moved rearwardly to its limit of motion, and a tie member secured to said heel base at opposite sides of said notch and overlapping said heel beneath said notch. 40

7. In combination, a heel base having a dovetail opening extending back from its breast face and a notch extending inwardly from its rear face, a heel having a dovetail projection on its top face 45 formed to enter said opening at its forward end and to be moved rearwardly into full engagement with the walls thereof and a projection at its rear end formed to engage in said notch when said heel has been moved rearwardly to its limit of motion, and a tie plate secured to 50 said heel base at both sides of said notch to prevent the sides of said notch from spreading in service. 55

8. In combination, a heel base having a dovetail opening extending back from its breast face 55 and a notch extending inwardly from its rear face, a heel having a dovetail projection on its top face formed to enter said opening at its forward end and to be moved rearwardly into full engagement with the walls thereof and a projection 60 at its rear end formed to engage in said notch when said heel has been moved rearwardly to its limit of motion, and a tie plate pivotally secured to said heel base at one side of said notch and releasably secured to said base at the other side of said notch to prevent the sides of said notch from spreading in service. 65

9. In combination, a heel base having a dovetail opening extending back from its breast face and a notch extending inwardly from its rear face, a heel having a dovetail projection on its top face 70 formed to enter said opening at its forward end and to be moved rearwardly into full engagement with the walls thereof and a projection at its rear end formed to engage in said notch 75

when said heel has been moved rearwardly to its limit of motion, and a tie plate pivotally secured to said heel base at one side of said notch and releasably secured to said base at the other side of said notch to prevent the sides of said notch from spreading in service, said plate overlapping the rear end of said heel when in operative position.

10. In combination, a heel base having a dovetail opening extending inwardly from its breast face and a heightwise notch extending inwardly

from its rear face, a heel having a dovetail projection on its top face formed to enter said opening at its forward end and to be moved rearwardly into full engagement with the walls thereof and a projection at its rear end formed to engage in 5 said notch when said heel has been moved rearwardly to its limit of motion, and an elastic band surrounding said heel and base and bridging from one to the other and retaining the portions on opposite sides of said notch against spreading. 10
